(57) **CLAIM**

The ornamental design for a coffee press as shown and described.

DESCRIPTION

FIG. 1 is a perspective view of a coffee press showing our new design, the outer cylinder of which being shaded to indicate translucency;

FIG. 2 is a side view thereof;

FIG. 3 is another side view thereof;

FIG. 4 is another side view thereof;

FIG. 5 is another side view thereof;

FIG. 6 is a top view thereof;

FIG. 7 is a bottom view thereof;

FIG. 8 shows the plunger partially inserted into the outer cylinder in a configuration of use;

FIG. 9 shows the plunger partially inserted into the outer cylinder in a configuration of use; and,

FIG. 10 is a sectional view taken along the plane shown in FIG. 2.

The dashed and broken lines in the figures show portions of the coffee press that form no part of the claimed design.

1 Claim, 10 Drawing Sheets
